TOOL FOR FLARING TUBES

Henry Edward Maupin, Portsmouth, Ohio

Application April 29, 1939, Serial No. 270,838

5 Claims. (Cl. 153—79)

The present invention relates to tools which are used for flaring tube ends and is an improvement over tools of this type.

The principal object of the present invention is to provide a tool for flaring tube ends which is economical to produce and which can be readily used in close quarters.

Another important object of the present invention is to provide a tool for flaring tube ends, 10 which members thereof automatically cooperate to position the tube end being flared in order that they may produce a symmetrical flange upon the tube end.

Another object of the present invention is to 15 provide a tool for flaring tubes which can be readily operated by hand without using additional tools but yet which is smooth, forceful and regular in its operation.

Further objects of the invention will be in part 20 pointed out and in part obvious in the following detailed description based upon the accompanying drawing.

In the drawing:

Fig. 1 is a side elevation of the tool comprising 25 the present invention.

Fig. 2 is a top cross sectional view of the tool taken upon line 2—2 of Fig. 1.

Fig. 3 is an end cross sectional view of the tool taken upon line 3—3 of Fig. 1 and having the 30 tube to be flared in position.

Fig. 4 is an end view similar to Fig. 3 but showing the position of the members upon the flaring of the tube end.

Fig. 5 is an end view of the tube supporting 35 members taken on line 5—5 of Fig. 2.

Fig. 6 is a cross sectional view of the opposite end of the tube supporting member taken on line 6—6 of Fig. 2, and

Fig. 7 is a top view of the tube supporting 40 members in their partially open position.

Referring now more particularly to the accompanying drawing wherein like reference characters refer to similar members, numeral 1 designates a substantially U-shaped block which is 45 formed by a pair of jaws 2 and 3 connected at one of their ends by a base portion 4. Base portion 4 has a threaded bore 5 formed through a central portion thereof. Rotatably mounted within said bore 5 is a shaft 6 having threads 7 upon its periphery, which threads 7 are in threaded engagement with the threads of bore 5. The upper end of shaft 6 has a block 8 mounted thereon and in fixed connection therewith. Said block 8 has a horizontal opening 9 formed there- 50 through in which is slidably mounted a lever 10,

whereby said lever 10 can be caused to extend at will of user upon opposite sides of block 8.

The opposite or lower end of shaft 6 has a cone-shaped member 11 fixedly connected thereto. Said cone-shaped member 11 has the lower 5 peripheral wall 12 thereof tapering inwardly at a 45° angle relative to the axis of shaft 6 and terminates in a point 13 which is in line with said axis.

The upper portion of the interior walls 15 of 10 jaws 2 and 3 extend substantially parallel to the axis of said shaft 6 whereas the lower interior wall portions 16 thereof flare inwardly towards one another at a 30° angle relative to said axis of shaft 6 and are positioned an equal distance 15 upon each side of said axis. Said jaws 2 and 3 terminate at their lower end with a flat wall 17.

A pair of equal width bars 18 and 19 are each 20 pivotally connected by pins 20 to a link 21. Said bars 18 and 19 each have a series of graduated 20 semi-circular recesses 22 formed upon their opposed faces in such a manner that when said bars 18 and 19 are placed adjacent one another, a series of graduated bores 23 are provided, with the axes thereof centered between walls 25. The 25 walls of said bores 23 taper outwardly at their upper end to provide seats 24, which seats 24 taper at a 45° angle relative to the axes of the bores 23. The exterior walls 25 of bars 18 and 19 taper from the upper face thereof inwardly 30 towards the lower face 26 at a 30° angle relative to the axes of bores 23. Said face 26 is substantially flat and extends substantially at right angles to said axes of bores 23. Bar 18 has a pin 27 mounted therethrough which extends from the 35 interior face thereof for entering a diametrically opposed opening 28 formed through bar 19 and thereby retaining said bars 18 and 19 in a given position relative to one another in order that the recesses 22 evenly meet with one another to provide bores 23 and also to present lower faces 26 extending contiguous from one another. In operation, lever 10 is given a circular movement for 40 rotating shaft 6. Upon shaft 6 being given a righthand rotation, cone-shaped member 11 will 45 be raised towards base portion 4. A tube 40 is then positioned between bars 18 and 19 in the pair of diametrically opposed recesses 22 which provide a bore 23 of the size corresponding to the circumference of the tube. Said bars 18 and 19 50 are pivoted upon link 21 towards each other for enclosing the tube within the cavity and also positioning pin 27 within opening 28 of bar 19. The assembled unit is then positioned within jaws 2 and 3 of block 1 with tapered walls 25 of 55

bars 18 and 19 supported by the correspondingly tapered interior wall 16 of jaws 2 and 3. Said walls 25 being tapered at a 30° angle relative to the axis of shaft 6 will also be positioned at the same angle relative to the axis of tube 40, since bores 23 and tube 40 will have a common axis which is in line with the axis of shaft 6 due to said wall 16 being flared at a 30° angle relative to the axis of bores 23 and walls 25 will therefore receive said walls 16 and position the axis of tube 40 in line with the axis of shaft 6 while, at the same time, allowing bars 18 and 19 to be longitudinally slidable.

Upon shaft 6 being given a lefthand rotation, 15 the cone-shaped member 11 will be directed towards the bore 41 of tube 40. Upon the tapered walls 12 contacting the wall of bore 41, the cone-shaped member 11 will gradually tend to evenly position itself within said bore 41 and will therefore cause bars 18 and 19 to longitudinally slide upon interior walls 16 until the point 13 of cone-shaped member 11 is in perfect alignment with the axis of tube 40. Continued downward movement of cone-shaped member 11 causes the 25 spreading of the upper edge of tube 40 due to the spinning motion and wedge-like action of said member 11. Bars 18 and 19, together with tube 40, will be forced downwardly between walls 16 and because of the downwardly tapering position of wall 16, bars 18 and 19 will be forced towards one another with an increasing amount of force as they are moved downwardly, thereby increasing the gripping action of the walls of the cavities 22 upon the periphery of 30 tube 40 for preventing any possible movement thereof while under the pressure exerted by member 11.

Shaft 6 is given a lefthand rotation until such time as cone-shaped member 11 has spread 40 the tube 40 sufficiently for the periphery thereof to contact seat 24, at which time the tube 40 will have a flange 42 as shown in Fig. 4 of the drawing, which extends outwardly at an angle relative to the axis of the tube equal to the angle 45 of taper of wall 12 and seat 24.

Upon reversing the rotation of shaft 6, cone-shaped member 11 is withdrawn from the tube 40 and block 1 is free to be removed from the tube supporting members, bars 18 and 19. Said 50 bars 18 and 19 can then be pivoted upon their pins 20 away from one another for detaching the tube 40 from within the recesses 22.

As can best be noted in Figs. 3 and 4 of the drawing, the lower edges 17 of jaws 2 and 3 form 55 with the lower faces 26 of bars 18 and 19 a flat continuous surface around the tube end being flared and in this manner, the present tool can be used upon tube ends of which only a small portion of the tube extends beyond a surface or 60 surrounding members and inasmuch as the operating member of the tool is at the opposite end of the tool from the tube being flared, the entire tool can be readily positioned among machinery and the like for performing its operation.

Whereas, it has hereinbefore been specifically mentioned that the tapered portion 12 and seats 24 are formed at a 45° angle while the walls 25 and interior walls 16 are formed at a 30° angle, it is obvious that these specific notations of degree can be varied to obtain the same results. However, the angle of walls 25 and walls 16 relative to the axis of the tube and the shaft 6 should be smaller than the angle of taper of 70 portion 12 and seat 24 inasmuch as tapered por-

tion 12 should form a wider angle than the sum of the angles of the walls 25 to give a spreading effect to the tube 40, which should be counteracted by the walls 16 and 25.

The present invention as herein disclosed is 5 capable of considerable modification and such changes from the device herein described and disclosed as come within the scope of the appended claims is deemed to be part of the present invention. 10

I claim:

1. An improvement in tools for flaring tubes comprising a pair of jaws, a base member joining an end portion of said jaws, said base member having a bore formed therethrough, a shaft 15 movably mounted through said bore, a cone-shaped member connected to said shaft, the opposite end portion of said jaws having their opposing faces flared downwardly toward one another and a tube supporting bar having the sides 20 thereof tapered to fit between and be longitudinally slidably supported by said opposing faces of the pair of jaws.

2. An improvement in tools for flaring tubes comprising a pair of jaws, an end portion of 25 each of said jaws having the side thereof opposing said other jaw flared towards the similar side of the other jaw, a base member joining the opposite end portion of said jaws to one another, said base member having a bore formed therethrough, a shaft slidably mounted through said bore, a cone-shaped member connected to said shaft and having a wider angle of taper than the angle formed between said flared sides 30 and a tube supporting bar having the sides thereof tapered to fit between and be longitudinally slidably supported by said flared sides.

3. An improvement in tools for flaring tubes comprising a pair of opposed jaws each having 40 a portion of the inner side thereof formed oblique, a base member joining said jaws with their oblique portions extending toward one another, said base member having a threaded bore formed therethrough, a threaded shaft rotatably mounted through said bore in threaded engagement therewith, a cone-shaped member carried by said shaft and having the point thereof in line with the axis of said shaft and a tube supporting bar longitudinally slidably supported 45 by said oblique portion of said jaws and having the sides thereof each inclined at an angle relative to the axis of the tube supported thereby equal to the angle of inclination of the adjacent oblique portion relative to the axis of said shaft. 55

4. An improvement in tools for flaring tubes comprising a base member, said base member having a threaded bore formed therethrough, a threaded shaft rotatably mounted through said bore in threaded engagement therewith, a pair 60 of diametrically opposed jaws, a portion of the opposing sides of said jaws having a downward inclination toward one another, said base member joining said jaws with their inclined portions extending toward one another at a given 65 angle relative to the axis of said shaft, a cone-shaped member connected to said shaft having the point thereof in line with the axis of said shaft and tapering at a wider angle than the given angle between said jaw inclined portions 70 relative to said axis, a supporting bar having a series of graduated openings formed therethrough, said bar openings having a portion thereof tapered for receiving a portion of said cone-shaped member, and the sides of said bar 75

being inclined relative to the axis of said openings at an angle equal to said given angle.

5. An improvement in tools for flaring tubes comprising a base member, a pair of jaws joined at their upper portion to said base member, a cone-shaped member, means slidably carried by said base member for moving said cone-shaped member between said jaws when desired, the

lower portion of said jaws being inclined towards one another, a tube supporting bar longitudinally slidably supported by and between the inclined portion of said jaws, and the lower face of said bar extending in line with the end face of the 5 lower portion of said jaws.

HENRY EDWARD MAUPIN.
